UNITED STATES PATENT OFFICE

KOLOMAN REZSNY, OF BUDAPEST, HUNGARY, ASSIGNOR TO HYDROMETER A. G., OF BRESLAU

BOILER FEEDING DEVICE

Application filed October 29, 1929, Serial No. 403,348, and in Germany November 5, 1928.

The present invention relates to boiler feeding devices.

In boiler feeding devices, more particularly for locomotives, for instance in exhaust steam injectors, automatic starters are already known. The hitherto used starters of this kind are however built into the exhaust steam injectors themselves, owing to which the construction of the latter is rendered complicated and their maintenance difficult. These disadvantages are remedied by the invention, a further advantage of which is that the exhaust steam can only pass into the injector when the latter is working as an ordinary injector, that is to say, the exhaust steam injector is first started with cold water before exhaust steam is admitted, which ensures a reliable starting even at high outside temperatures. A further characteristic feature of the invention is the special construction of the exhaust steam injector.

In the accompanying drawings two constructional forms of the invention are shown by way of examples.

Figure 1 shows the arrangement of the starter and of the exhaust steam injector on a locomotive.

Figure 2 is a longitudinal section through the starter,

Figure 3 a longitudinal section through the exhaust steam injector.

Figure 4 is a section on the line A—A of Figure 3.

Figure 5 is a side view of another constructional form of the invention.

Figure 6 is a top view of the same constructional form.

Figure 7 is a longitudinal section.

Figure 8 is a longitudinal section on the line B—B of Figure 5 after that the nozzles have been removed.

From the exhaust pipe 1 of the steam cylinders of the locomotive a connection pipe 2 is carried to the starter 3, and the exhaust steam passes from the latter through a pipe 5 to the exhaust steam injector 6 into which the feed water is let through the connection pipe 7 from the water space 8 of the tender, the quantity of which feed water may be regulated by means of the

handle 9. The feed water flows from the pipe 7 through a valve 35 (Fig. 4) into a chamber 33 in the injector 6 and in the mixing nozzle 32 becomes mixed with the exhaust steam, which passes into the mixing nozzle 32 through the steam nozzle 31. The valve 35 works as a check valve and its lift may be regulated by means of a screw spindle 36, which is arranged in the casing 34, and the handle 9. From the nozzle 32 the water passes at raised velocity and raised temperature into a chamber 37 in which a temperature of 50–70° C. and a pressure of 3–5 atmospheres is attained. From this chamber the water flows into the upper part of the exhaust steam injector. This comprises a live steam nozzle 24, a mixing nozzle 25 and a delivery nozzle 26. The live steam is conducted to the live steam nozzle 24 through the live steam valve 10 and the live steam pipe 11. The mixing nozzle 25 is surrounded by the overflow chamber 27, which is shut off from the overflow pipe 13 by the automatic overflow valve 28. The overflow water passes through the overflow pipe 13 into the return pipe 14 of the tender. This pipe is preferably carried through the water space of the tender in such a manner, that the heat of the overflow water is transmitted to the tender water, and the overflow water flows at the top back into the water space of the tender. Above the delivery nozzle 26 a delivery valve 29 is arranged, which works as a check valve and separates the feed pipe from the delivery chamber 30.

The starter is connected by means of a small steam pipe 15 to the steam space of the slide valve chest or to the steam admission pipe, and also by a second small pipe 16, to the live steam pipe 11.

The starter 3 comprises (Figure 2) two identical casings 17 and 17a, in each of which there is a valve 18 or 18a on a seat 19 or 19a. In the said casings are mounted cylinders 20 and 20a to which lead the pipes 15, 16. The cylinder 20 is therefore in connection with the steam admission pipe or with the admission chamber of the slide valve chest, and the cylinder 20a with the live steam pipe 11. The last mentioned cyl-

inder may however instead of being connected to the pipe 11 be in connection with the delivery chamber of the injector. In the said cylinders pistons 21, 21a are arranged by means of which the valves 18, 18a are opened, which normally are kept closed by pressure springs 22, 22a mounted on the valve rod.

The injector operates in the following manner:

10 As the return pipe 14 opens at the top above the water level in the tender, the casing of the exhaust steam injector is always filled through the connection pipe 7 with the cold water which fills the exhaust steam pipe 5 also up to the starter 3. When the locomotive is running without steam or is standing still and is to be fed, the live steam valve 10 is opened, whereupon a pressure is produced in the exhaust steam injector, which 15 closes the water valve 35 and opens the overflow valve 28. The live steam forces therefore the water from the overflow chamber 27 through the overflow pipe 13 and the return pipe 14 back into the tender. A slight 20 vacuum is then produced, and fresh water will flow in through the water valve 35. The injector starts and works as an ordinary injector. In the live steam pipe 11 there will now be substantially the full boiler 25 pressure, so that the valve 18a in the starter will be opened. As however there is as yet no pressure in the cylinders or in the steam admission pipe, the valve 18 will remain closed, and the starter 3 will shut off the connection 30 between the exhaust pipe 1 and the exhaust steam injector 6. No air will be therefore able to pass into the injector.

When the locomotive is running under steam, and it is desired to do the feeding, the 40 exhaust steam injector is again started working by a single operation by means of the live steam valve 10. The valve 18 of the starter will be opened by the steam pressure in the slide valve chest or in the steam admission pipe and the valve 18a will be opened by the pressure in the live steam pipe 11. The 45 exhaust steam will then be able to pass into the bottom part of the exhaust steam injector through the exhaust steam nozzle 31 and will become mixed with the cold feed water so that the water will be highly preheated before it passes into the upper part of the injector. When working with exhaust steam, the feed water passes into the chamber 37 50 not only highly preheated, but also with a considerable pressure owing to the delivery nozzle 32, so that the live steam valve 10 must be correspondingly throttled, immediately after the starting.

55 The arrangement of the valves 18, 18a is such that great changes of direction are produced in the exhaust steam, owing to which oil, water, dirt, etc. will be separated in the bottom part of the casings 17, 17a and may be discharged through cocks 23 and

23a. Into these cocks also automatic water outlet devices may be built.

The described arrangement of the overflow tube 13 and the pipe 14 has three advantages:

(a) The hitherto wasted quantity of overflow water is saved, and the quantity of heat hitherto lost with the overflow water, is recuperated. This quantity is considerably more particularly when the injector is working in an unreliable manner.

(b) The water valve 35 may be always open with a correspondingly adjusted lift, which greatly facilitates the work of the engine crew as only the live steam valve 10 has to be operated.

(c) There is always left in the pipe 14, 18 a water column which closes and loads the overflow valve 28, so that the pressure in the overflow chamber may be greater than the atmospheric pressure. The feed water may therefore have in the mixing nozzle 25 a considerably higher temperature than in the ordinary injectors, owing to which the exhaust steam can preheat the feed water to a higher temperature, more particularly as the feed water passes into the chamber 37 with a considerable pressure.

The working of the overflow pipe 14 is independent of the special construction of the exhaust steam injector, that is to say may be used for instance, also in ordinary injectors.

As indicated in Figures 5-8 a plurality of exhaust steam injectors of the kind described above, may be combined in a simple and efficient manner. According to prescriptions given by the authorities locomotives must be equipped with two separate and independent feeding devices of which one is used regularly whereas the other serves as a reserve and is used as a substitute when the former is damaged. Each injector must alone be able to deliver the required amount of feeding water. The reserve feeding device works exclusively with live steam, and is therefore uneconomical in use and because it only exceptionally is operated it is mostly not in order and will easily freeze.

According to the present invention at least two independent injectors are combined in such a manner that each may be used selectively or any desired number may be employed. If for instance a set of three injectors *a*, *b* and *c* of different effects are used seven different working relations (*a*, *b*, *c*; *a*-*b*; *a*-*c*; *b*-*c*; *a*-*b*-*c*) and control possibilities are obtained in accordance with the boiler yield at a given time. The rules are complied with when the arrangement is so dimensioned, that two injectors in combination are able to cover the entire water consumption of the boiler. If one injector should be damaged, the remaining pair will always be able to supply the necessary feed water. On account of the combination of a plural-

ity of injectors, all injectors may without difficulty be driven economically by means of exhaust steam. The safety of working is increased, because all injectors are kept in operation. Even when only a single injector is in use the entire set will be maintained at a raised temperature and the water will be kept moving, whereby the danger of freezing is minimized.

10 In the casing 41 for instance three live steam injectors 42 (Fig. 7) of different effects may be arranged independently of each other and side by side in chambers 43-45 (Fig. 8) and in the lower chambers 47-49 three exhaust injectors may be located. The live steam from the boiler does not as shown in Figure 1 pass through a single live steam valve 10 and a single pipe 11 but flows through three mutually independent live steam valves and pipes into the live steam injectors 42. The feed water is supplied to the exhaust steam injectors 46 from the tender through the connecting pipe 7, in the manner described in connection with Figure 25. 1. In this pipe a cock 35 is arranged, which (as in Fig. 1) may be turned by means of the handle, in order to regulate the quantity of feeding water to be delivered.

20 In each of the nozzles 31 of the exhaust steam injectors is a threaded spindle 50, the nozzle end of which is equipped with a substantially conical body (pear) 51, which may be displaced by rotating the spindle. By means of this simple mechanism it is possible to alter the free cross-sectional area of the exhaust steam nozzle 31 and thereby to regulate the quantity of the exhaust steam.

25 The exhaust steam pipe 5 connecting the engine of the locomotive with the feeding device is widened adjacent the injector casting 41 and in this widened part 52 three independent exhaust steam inlet devices are arranged side by side. Each device consists of the steam cylinder 53 with a piston 54, the valve 55 with a spring 56 and a spring seat 57 and the steam supply socket piece 58. The part of the spring rest on which the spring is resting is ball shaped, so that the valve always will be uniformly pressed against the valve seat. The three steam supply socket pieces 58 are by means of three pipes connected to the three live steam pipes and when one of the injectors receives live steam through the pipes the corresponding exhaust steam inlet device is opened and the exhaust steam will flow into the corresponding exhaust steam injector. The steam supply socket pieces 58 might however also be connected to the individual delivery chamber 59 of the live steam injectors.

30 As usual each live steam injector comprises a check valve 60, which opens into a common collecting chamber 61 for the feed water. From this chamber the feed water is pressed into the boiler through the pipe 12. Each

live stem injector is further as usual equipped with an overflow valve 62 through which the overflow water passes into a common overflow chamber 63 from which the water flows back into the tender or another suitable receptacle through the pipe 13 and the return conduit 14.

35 The starter shown in Fig. 2 consist here of two different parts. The front part 17-22, which is operated by engine steam is still in the exhaust steam pipe 2 and has therefore not been specially illustrated. The rear part 17a-22a is now present in a triple arrangement and is located immediately in front of the injectors. The reference numerals 53-58 denote the rear part of the starter in this constructional form of the device. Principally this starter is of the same kind as that shown in Fig. 2. The starter may of course also be constructed in such a manner, that the front part 17-22, which is operated by the engine steam, remains unchanged and is directly coupled to the rear part 53-58 in a number corresponding to the number of injectors, whereby a separate exhaust steam pipe 5 is arranged for each injector. In this constructional form of the invention the entire starter is thus separated from the injector casing.

40 The effect is similar to that described in connection with the arrangement illustrated in Figures 1-4. When the engine works the exhaust steam flows continually through the front part of the starter to the feeding device and in accordance with the effect of the locomotive the live steam is let into the injectors through one, two or three live steam pipes by means of the manually operated valves 10. In accordance with the number of live steam pipes which are open at a given time the corresponding inlet valves 55 are opened, and the exhaust steam will operate the injectors, which at this time are working, whereby the feed water is forced into the boiler.

45 It lies within the scope of the invention to arrange so called compound-exhaust steam- and live-steam injectors side by side at which the live steam is mixed with exhaust steam, whereupon the mixed steam is brought into contact with the feed water.

50 The throttling of the exhaust steam in the exhaust steam nozzle 31 may also be carried out automatically, for instance by moving the spindle 50 axially by means of a thermostat. The spindle 50 may also be operated from above, for instance from the driver's stand, by means of special handles.

55 It also lies within the scope of the invention to equip each of the injectors of the kind shown in Figures 5-8 with a separate feed pipe 12 or a separate return pipe 13. Also the fresh water may be conducted to each injector through a separate pipe.

60 Having now particularly described and

ascertained the nature of my said invention and in what manner the same is to be performed, I declare that what I claim is:—

1. In a boiler feeding device, especially for locomotives, a two-stage injector, the first stage being started with live steam while cold water passes through the second stage, an exhaust steam starter separated from the injector in the exhaust steam pipe of the slide valve chest of the locomotive, said starter consisting of a pair of automatically closing valves arranged one behind the other for regulating the supply of steam to the injector, the exhaust steam of the locomotive being only admitted in the second stage of the injector when the injector delivers as live steam injector.
2. In a boiler feeding device, especially for locomotives, a two-stage injector, an exhaust steam starter separated from the injector in the exhaust steam pipe of the slide valve chest of the locomotive, said starter having two automatically closing valves arranged one behind the other and each having a piston adapted to slide in a cylinder while the cylinder of the first valve communicates with the admission chamber of the slide valve chest through a pipe subjected to the live steam pressure and the cylinder of the second valve communicates through a pipe which is in communication with the delivery chamber of the said exhaust steam injector.
3. In a boiler feeding device, especially for locomotives, a two-stage injector, an exhaust steam starter separated from the said injector in the exhaust steam pipe of the slide valve chest of the locomotive, said exhaust steam starter having two automatically closing valves, one arranged behind the other and chambers with discharge cocks provided beneath the same in the casing for the separation of oil, water and other impurities in the exhaust steam by a change of direction of the exhaust steam when passing through said valves.

In testimony whereof I affix my signature.
KOLOMAN REZSNY.
